(57) **CLAIM**

We claim the ornamental design for the paper tab, as shown and described.

DESCRIPTION

FIG. 1 is a front view of the paper tab showing our new design;

FIG. 2 is a rear view of the claimed design.

FIG. 3 is a side view of the claimed design.

FIG. 4 is a top view of the claimed design.

FIG. 5 is a bottom view of the claimed design;

FIG. 6 is a perspective view of the claimed design; and,

FIG. 7 is a perspective view of the claimed design in use. The broken lines in FIG. 7 are included for the purpose of showing environmental subject matter that forms no part of the claimed design.

1 Claim, 4 Drawing Sheets
